HOLDER FOR A SEAL BEAM LAMP

Richard T. Kennedy, Oak Lawn, and James L. Hvale,
Chicago, Ill., assignors to Bell Electric Company,
Chicago, Ill.

Filed Oct. 29, 1973, Ser. No. 410,737

Term of patent 14 years

Int. Cl. D26—03

U.S. Cl. D48—20 K

FIG. 1

FIG. 2

FIG. 3

FIG. 4

FIG. 5

FIG. 7

FIG. 6

FIG. 1 is a perspective of a holder for a seal beam lamp showing our new design;

FIG. 2 is a top view thereof;

FIG. 3 is a bottom view thereof;

FIG. 4 is a front elevational view thereof;

FIG. 5 is a side elevational view thereof;

FIG. 6 is an elevational view of the side opposite the side as shown in FIG. 5; and

FIG. 7 is a rear elevational view thereof.

The post is broken away to indicate indeterminate length.

We claim:

The ornamental design for a holder for a seal beam lamp, substantially as shown and described.
